UNITED STATES PATENT OFFICE.

ALEXANDER C. DUMONTIER, OF DETROIT, MICHIGAN.

DESIGN FOR A LUNCH AND PARCEL CARRIER.

SPECIFICATION forming part of Design No. 28,241, dated February 1, 1898.

Application filed July 6, 1897. Serial No. 643,665. Term of patent 14 years.

To all whom it may concern:

Be it known that I, ALEXANDER C. DUMONTIER, a citizen of the United States, residing at Detroit, in the county of Wayne, State of Michigan, have invented and produced a new and original Design for Lunch and Parcel Carriers, of which the following is a specification, reference being had to the accompanying drawings, and to the letters of reference marked thereon, which form a part of this specification.

This invention relates to a design for a lunch and parcel carrier; and it consists in the formation and contour illustrated in the accompanying drawings, in which—

Figure 1 is a perspective view of my design for a lunch and parcel carrier. Fig. 2 is a transverse section therethrough on line 2 2 of Fig. 1.

The main feature of my design consists of a hollow polygonal case A, oblong in form, the base of which is flat, as shown at B, and the body portion immediately above the base is substantially rectangular. The bottom of

the ends C of said base are approximately 25 square, while the top portion thereof is curved, so as to describe a semicircle D. The top portion or cover E of said case is rolling, extending in the arc of a circle from the back to the front of the case in an unbroken line andlapping onto the front side thereof, said lapping portion describing a curved line G across the front of the case and being provided with a fastening-button E'. A curved handle F is mounted on said cover and stands parallel to 35 the longitude thereof, the whole presenting a new and original design for a lunch and parcel carrier.

Having thus fully set forth my invention, what I claim is—

40 A design for a lunch and parcel carrier substantially as shown and described.

In testimony whereof I affix my signature in presence of two witnesses.

ALEXANDER C. DUMONTIER.
